MUDGUARD FOR A CYCLE OR SIMILAR ARTICLE

Norman G. Wintermantel, Palos Heights, Ill., assignor, by
mesne assignments, to American Machine & Foundry
Company, New York, N. Y., a corporation of New
Jersey

Application February 28, 1956, Serial No. 49,402

Term of patent 14 years

(Cl. D34—15)

FIG. 1

FIG. 2

Fig. 1 of the drawing is a side elevation of a mudguard for a cycle or similar article, showing my new design; and

Fig. 2 is a horizontal sectional view taken on line 2—2 of Fig. 1, looking in the direction of the arrows. The broken lines are for illustrative purposes only.

I claim:

The ornamental design for a mudguard for a cycle or similar article, as shown and described.
